COMBINATION TIE PLATE AND RAIL JOINT

Irvin Young, Falmouth, Ky.

Application October 8, 1945, Serial No. 620,938

2 Claims. (Cl. 238—188)

1

This invention relates to a combination tie plate and rail joint and has for its primary object to distribute the load imposed upon a rail joint over a group of ties.

Another object is to facilitate the proper aligning of a pair of the butting railroad rails for clamping engagement by the rail clamps of the rail joint.

The above and other objects may be attained by employing this invention which embodies a bridging plate adapted to embrace at least three ties, said bridging plate having a transversely extended depression intermediate its ends and overhanging flanges at opposite ends of the depressions, spaced parallel ribs adjacent opposite ends between which the rail flanges are adapted to be received for proper alignment within the rail joint, and rail clamps slidably transversely of the depression and having flanges at opposite ends for engagement beneath the overhanging flanges for the purpose of improving the stability of the rail joint.

Other features include rail flange embracing members carried by the rail clamps and vertically extending rail web engaging members between which opposite ends of abutting rails are clamped.

Referring to the drawings:

Figure 1 is a perspective view of a rail joint and tie plate embodying the features of this invention, showing a group of railway ties and the abutting ends of a railway rail in place.

Figure 2 is a perspective view of the bridging plate.

Figure 3 is a perspective view of one of the rail clamps, and

Figure 4 is a transverse sectional view through the assembled device illustrated in Figure 1.

Referring to the drawings in detail a railroad road bed designated generally 10 includes ties 11 and rails 12. At the junction of abutting rails throughout the entire length of the road bed 10 I provide my improved combination tie plate and rail joint, designated generally 13, which comprises a bridging or bed plate 14, carrying at opposite ends depending flanges 15, which are adapted to overhang and engage the outer opposite faces of the endmost ties 11. As illustrated, I prefer to have the bridging, or bed plate 14, of a length sufficient to cover at least three of the cross ties 11, so that the weight of the joint will be well distributed and its stability improved. Formed intermediate the ends of the bridging or bed plate, 14, is a depression 16 opposite ends of which are provided with overhanging flanges 17 for a purpose to be more fully

2

hereinafter described, and formed at space intervals in the bed plate are pairs of spaced apertures 18 through which suitable fastening screws 19 are adapted to enter to be driven into the cross ties 11, as illustrated in Figure 1. Formed on the upper side of the bed, or bridging plate 14 adjacent opposite ends are spaced longitudinally extending parallel ribs 20 and the distance between these ribs is sufficient to accommodate the flanges 10 of the rails 12 previously referred to.

Slidably mounted in the depression 16 of the bridging or bed plate 14 are rail clamps designated generally 21 each of which comprises a plate 22 carrying at opposite ends, horizontally extending flanges 23 which are adapted to engage beneath the overhanging flanges 17 when the clamps 21 are in place, as shown in Figure 1. Formed adjacent the inner edge of each plate 22 is a thickened member 24 which is provided along 20 its innermost surface with a rail flange embracing recess 25 and rising upwardly from the innermost edge of the thickened portion 24 is a rail web engaging and supporting member 26. This rail web engaging flange 26 is formed with pairs 25 of spaced apertures 27 which are adapted to register with similar apertures formed adjacent the abutting ends of the rails 12 to receive suitable clamping bolts 28.

In use, it will be understood that the bridging plate 13 is positioned on the ties as illustrated in Figure 1 and secured into place by the introduction of the screws 19 through the openings 18 adjacent opposite ends of the plate. The rails are then placed into position on the bridging or bed plate with their abutting ends meeting substantially midway of the depression 16 whereupon the rail clamps 21 are placed in position against the rails 12 by entering the flanges 23 beneath the flanges 17 and sliding the clamps 40 toward one another in the recess 16. As the clamps approach one another, the flanges 26 will move into engagement with the webs of the rails 12 with the openings 27 aligning with the openings formed adjacent the ends of the rails. The bolts 28 may then be introduced and upon drawing the bolts tight the walls of the recesses 25 will embrace the rail flanges as shown in Figure 4, to provide a firm seat beneath the bottom of the rails. Having drawn the clamps 21 into proper place they are locked therein by entering screws 19 through openings 29 formed in the horizontally extending portions of the plates 22 and passing these bolts downwardly through the openings 18 formed in the portion of the bed or bridging plate 14 which is of reduced thickness

and thence into the cross tie, which extends transversely of the device, midway of its length. By drawing all of the screws 19 tightly into place and drawing up the bolts 28 it is obvious that a substantially unitary structure will be formed about the abutting ends of the rails which will effectively secure the rail joint against separation by vibration and wear. The flanges 20 serve as guides in placing the rails in proper abutting position on the bridging or bed plate 14 and furthermore tend to aid in producing a solid joint.

What I claim is:

1. In a combination tie plate and rail joint, a bridging plate adapted to extend over at least three ties, a depending flange at each end of the bridging plate adapted to overhang the sides of ties supporting opposite ends of the bridging plate, spaced parallel rail engaging ribs extending longitudinally of the bridging plate adjacent each end thereof, a pair of oppositely movable rail clamps, slidably mounted on the bridging plate, each rail clamp comprising a vertically extending rail web engaging portion, a horizontally extending rail flange embracing portion, a laterally extending stabilizing and anchoring flange projecting outwardly from the rail flange embracing portion, said bridging plate having longitudinally spaced pairs of openings along each side edge, each rail clamp having a pair of openings which are adapted to align with certain of the openings in the bridging plate when the clamp plates are in rail clamping position, screws extending through the openings and securing the bridging plate to ties upon which it rests, and clamps against the rails, and bolts extending through the clamps and the web of a railroad rail for securing the rails in place.

2. In a combination tie plate and rail joint, a bridging plate adapted to extend over at least three ties, a depending flange at each end of the bridging plate adapted to overhang the sides of ties supporting opposite ends of the bridging

plate, said bridging plate having a transversely extending depression midway of its length, overhanging flanges at opposite ends of the depression, rail clamps slideable transversely in the depression, flanges at opposite ends of the rail clamps for engagement beneath the overhanging flanges, a rail flange embracing portion on each rail clamp, a rail web engaging portion on each rail clamp, spaced parallel rail positioning ribs on the upper face of the bridging plate adjacent opposite ends whereby the abutting ends of adjacent rails may be properly aligned on the bridging plate for engagement by the rail clamps, said bridging plate having longitudinally spaced pairs of openings along each side edge, each rail clamp having a pair of openings which are adapted to align with certain of the openings in the bridging plate when the clamp plates are in rail clamping position, screws extending through the openings and securing the bridging plate to ties upon which it rests and the clamps against the rails and bolts extending through the clamps and the web of a railroad rail for securing the rails in place.
